UNITED STATES PATENT OFFICE

159,149

COMBINED RACK AND CHILD'S EATING IMPLEMENT

Marvin Glass, Chicago, Ill., assignor to Grove &
Glass, Inc., Chicago, Ill., a corporation of Illinois

Application January 16, 1948, Serial No. 143,823

Term of patent 14 years

(Cl. D44—29)

To all whom it may concern:

Be it known, that I, Marvin Glass, a citizen of the United States, residing at Chicago, county of Cook and State of Illinois, have invented a new, original, and ornamental Design for a Combined Rack and Child's Eating Implements, of which the following is a specification, reference being had to the accompanying drawing, forming a part hereof.

Fig. 1 is a front view of a combined rack and child's eating implements, showing my new design.

Fig. 2 is a rear view thereof, and
Fig. 3 is a side view thereof.

I claim:

The ornamental design for a combined rack and child's eating implements, as shown.

MARVIN GLASS.
